UNITED STATES PATENT OFFICE.

WILLIAM J. SWAN, OF DETROIT, MICHIGAN.

DESIGN FOR A DRAWER-PULL.

SPECIFICATION forming part of Design No. 20,498, dated February 3, 1891.

Application filed November 24, 1890. Serial No. 372,536. Term of patent 3½ years.

To all whom it may concern:

Be it known that I, WILLIAM J. SWAN, of Detroit, in the county of Wayne and State of Michigan, have invented a new and original 5 Design for a Drawer-Pull, of which the following is a specification.

This design has for its object to provide a novel, ornamental, and characteristic drawer-pull; and its leading feature consists in a 10 curved inclined handle springing from an ornamental base.

In the accompanying drawings, Figure 1 is a front elevation of a drawer-pull embodying my design. Fig. 2 is a similar view showing 15 a variation in the vine or scroll-work. Fig. 3 is a detail edge view, on a reduced scale, of the form of pull shown in Fig. 2. Fig. 4 is a detail edge view of the form shown in Fig. 1.

A represents the handle of the pull, curved

and inclined diagonally across the pull. 20 From each end of the handle springs an ornamental base composed, as here shown, of a vine or scroll-work which branches in two directions, the two which spring from the upper side of the handle (marked B B) meeting 25 at the top center of the pull, and the two which spring from the lower side of the handle (marked C C) meeting at the lower center of the pull.

What I claim as my invention, and desire 30 to secure by Letters Patent, is—

The design for a drawer-pull herein shown and described.

WILLIAM J. SWAN.
